PERPETUAL CALENDAR

Louis Bernstein, Brooklyn, N. Y.

Application February 16, 1945, Serial No. 578,294

3 Claims. (Cl. 40—115)

1

This invention relates to new and useful improvements in calendars, and has more particularly reference to perpetual calendars.

More particularly the invention proposes a perpetual calendar which is characterized by a support sheet having an opening for viewing a year plate. It is proposed to movably mount the year behind said support sheet so that each year it may be turned to a new position and display the number of the year through the opening in said support sheet.

The invention proposes to turnably mount a small day of the week disc, and a medium month disc, and a large numeral disc coaxially with each other on the front of said support sheet. A stationary indicator is mounted on said support sheet and extends across said discs, and is provided with window openings for displaying one notation of each of said discs.

The invention also proposes imprinting the support sheet at areas around the large numeral disc with sections indicating the months, and sections indicating the holidays contained in each of the months.

The invention also proposes a modified form of perpetual calendar, embodying means for holding the discs from turning and adjustably to free the discs individually, or as a unit so that the discs may be individually turned or turned as a group.

Still further the invention proposes the construction of a perpetual calendar as briefly described, which may be manufactured and sold at a reasonable cost.

For further comprehension of the invention, and of the objects and advantages thereof, reference will be had to the following description and accompanying drawings, and to the appended claims in which the various novel features of the invention are more particularly set forth.

In the accompanying drawings forming a material part of this disclosure:

Fig. 1 is an elevational view of a perpetual calendar constructed in accordance with this invention.

Fig. 2 is a perspective view of the calendar shown in Fig. 1 but drawn on a reduced scale.

Fig. 3 is a vertical sectional view taken on the line 3—3 of Fig. 2.

Fig. 4 is a front elevational view of a perpetual calendar constructed in accordance with a modified form of this invention.

Fig. 5 is a fragmentary enlarged detailed view of a portion of Fig. 4.

2

Fig. 6 is a fragmentary enlarged vertical sectional view taken on the line 6—6 of Fig. 5.

Fig. 7 is a fragmentary enlarged sectional view taken on the line 7—7 of Fig. 6.

Fig. 8 is a fragmentary enlarged horizontal sectional view taken on the line 8—8 of Fig. 6.

The perpetual calendar, in accordance with that form of the invention disclosed in Figs. 1 to 3 inclusive, includes a support sheet 10 having an opening 11 for viewing a year plate 12 which is rotatively mounted upon a pintle pin 13 supported on the support sheet 10. The year plate 12 is imprinted with numbers, representing the years, which are viewable through the opening 12 when the year plate is turned to various positions.

As illustrated on the drawings it is in a position in which the year 1945 is displayed. It may be turned to display subsequent years, as needed.

20 The support plate 10 is provided with a large top area 15 which may be imprinted with a picture, or a puzzle, or other material to make the calendar attractive, and decorative.

25 A small day of the week disc 17 is superimposed upon a medium month disc 18, which in turn is superimposed upon a large numeral disc 19. These discs are coaxial with respect to each other, and are coaxially turnably mounted on said pintle pin 13. These discs are provided with serrations

30 21 upon their edges by which they may be conveniently turned. The discs 17 and 18 are separated from each other by a friction washer 22. The discs 18 and 19 are separated from each other by a friction washer 23, and the disc 19 is separated from the support sheet 10 by a friction washer 24. These friction washers are mounted on the pintle pin 13. They serve to hold the said discs against free turning. However, each disc can be manually turned.

35 The day of the week disc 17 is divided into seven peripheral areas imprinted with the days of the week; Monday, Tuesday, etc. The medium month disc 18 is divided into 12 areas which are imprinted with notations representing the months of the year, namely, January, February, etc. These areas are also imprinted with notations to indicate the numbers of days in each month, for example, January has 31 days, and February has 28 days, and leap years 29 days, etc.

40 45 50 The large numeral disc 19 is imprinted with 31 areas numbered from 1 to 31 and representing the days of the month.

55 The stationary indicator 27 is supported on the support sheet 10 and extends across said discs 17, 18 and 19, and is provided with window open-

ings 28 for displaying one notation of each of said discs. At the top, the indicator 27 is supported on a block 29 which is attached to the support sheet 10 with fastening elements 30. At the bottom, the indicator 27 is engaged over the pintle pin 13 and is securely held by the head of the pintle pin. The support sheet 10 has a top opening 32 by which it may be hung up on a nail, or other support on a wall, or other object.

The support sheet 10 is also imprinted with a circular area 34 about the large numeral disc 19 which is formed with sections 35 imprinted with the names of the months. Adjacent these sections 35 there are radiating sections 36 which are imprinted with the holidays contained in each month. For example, the month of March is imprinted as having St. Patrick's day on March 17.

The calendar is used by rotating the small day of the week disc 17 and the large numeral disc 19 each day so as to display the correct day. The medium disc 18 is turned each month so as to display the proper month. The year plate 12 is turned each year.

In Figs. 4 to 8 inclusive, a modified form of the invention has been disclosed which is very similar to the prior form distinguishing merely in the fact that means have been provided for holding the discs 17, 18 and 19 from turning, and this means is adjustable to free the discs so that they may be turned individually, or as a unit. This means includes a slide plate 40 engaged across the back of the indicator 27 and having edge portions 41 engaged around the edges of the indicator 27, and engaging cutouts 42 formed in the edge of the indicator 27 by which the slide plate 40 is limited to move a short distance upwards and downwards.

Leaf springs 43 are mounted upon the bottom of the support block 29 and engage the top edge of the slide plate 40 normally urging it into its bottom position. The slide plate 40 has window openings 44 which are aligned with the window openings 28 of the indicator 27 so as not to interfere with viewing the several discs through the window openings.

A plunger 46 is provided with each of the discs 17, 18 and 19 and each is slidably mounted through a tubular socket 47 fixedly mounted on the back of the slide plate 40. The stationary indicator 27 is formed with small vertical slots 48 through which the plungers 46 pass. These plungers 46 are square, in transverse cross section, and the sockets 47 are similarly shaped, limiting the plungers to slide inwards and outwards, and restraining them from turning. Each plunger 46 is provided with a knob 49 by which the plunger may be pressed inwards. Each plunger 46 has a small spring 50 located in back of the knob 49 and acting against the front face of the stationary indicator 27 for normally urging the plunger 46 outwards. Each plunger 46 has a tooth-like projection 51 on its inner end which normally engages the serrations 21 of said discs 17, 18 and 19. These tooth-like projections fixedly hold the discs from being turned.

The operation of this form of the invention is substantially identical to the prior form, distinguishing merely in the fact that it is necessary to free the discs 17, 18 and 19 before they may be turned. Each disc may be freed by pressing inwards the plunger 46 associated with the disc. When the knob 49 of a plunger 46 is pressed inwards, the tooth-like projection 51 will be

moved back and out from the serrations 21 in the disc, and it may be turned.

If it is desired to free the discs 17, 18 and 19 simultaneously so that they may be turned, as desired, without interference, the flanges 41 of a slide plate 40 are manually gripped and moved upwards. Thus the slide plate 40 is raised, lifting all of the tooth-like projections 51 out from the serrations 21. This is of particular advantage when the calendar was not used for some time and all of the discs are in wrong positions, and must be reset.

It is to be understood that this device may be used not only in connection with calendars but any other data may be inscribed on the various discs such as information about geographical locations, mathematical calculations, etc.

While I have illustrated and described the preferred embodiments of my invention, it is to be understood that I do not limit myself to the precise constructions herein disclosed and the right is reserved to all changes and modifications coming within the scope of the invention as defined in the appended claims.

Having thus described my invention, what I claim as new, and desire to secure by United States Letters Patent is:

1. A perpetual calendar, comprising a support sheet having an opening for viewing a year plate, a serrated small day of the week disc superimposed on a serrated medium month disc superimposed on a serrated large numeral disc coaxially turnably mounted on said support sheet, a stationary indicator supported on said support sheet and extending across said discs and having window openings for displaying one notation of each of said discs, a year plate turnably mounted in back of said support sheet, and means for holding said discs from turning and adjustably to free the discs individually, or as a unit, including a slide plate slidably mounted on said indicator and having window openings aligned with the window openings of said indicator, resilient means for urging said slide plate downwards, a plunger for each of said discs mounted on said slide plate through non-circular sockets, said plungers being non-circular and complementary to said sockets, and tooth-like projections on the ends of said plungers engaging the serrations on the discs.

2. A perpetual calendar, comprising a support sheet having an opening for viewing a year plate, a serrated small day of the week disc superimposed on a serrated medium month disc superimposed on a serrated large numeral disc coaxially turnably mounted on said support sheet, a stationary indicator supported on said support sheet and extending across said discs and having window openings for displaying one notation of each of said discs, a year plate turnably mounted in back of said support sheet, and means for holding said discs from turning and adjustably to free the discs individually, or as a unit, including a slide plate slidably mounted on said indicator and having window openings aligned with the window openings of said indicator, resilient means for urging said slide plate downwards, a plunger for each of said discs mounted on said slide plate through non-circular sockets, said plungers being non-circular and complementary to said sockets, and tooth-like projections on the ends of said plungers engaging the serrations on the discs, and resilient means urging said plungers outwards.

3. A perpetual calendar, comprising a support sheet having an opening for viewing a year plate,

a serrated small day of the week disc superimposed on a serrated medium month disc superimposed on a serrated large numeral disc coaxially turnably mounted on said support sheet, a stationary indicator supported on said support sheet and extending across said discs and having window openings for displaying one notation of each of said discs, a year plate turnably mounted in back of said support sheet, and means for holding said discs from turning and adjustably to free the discs individually, or as a unit, including a slide plate slidably mounted on said

10 indicator and having window openings aligned with the window openings of said indicator, resilient means for urging said slide plate downwards, a plunger for each of said discs mounted on said slide plate through non-circular sockets, said plungers being non-circular and complementary to said sockets, and tooth-like projections on the ends of said plungers engaging the serrations on the discs, edge portions of said slide plate being engaged around the edge portions of said stationary indicator.

LOUIS BERNSTEIN.
